(57) CLAIM

The ornamental design for a tongue depressor, as shown and described.

DESCRIPTION

FIG. 1 is a perspective view of a tongue depressor showing my new design;

FIG. 2 is a right side elevational view thereof;

FIG. 3 is a bottom plan view thereof;

FIG. 4 is a top plan view thereof; and,

FIG. 5 is a front elevational view thereof.

The broken lines showing the handle portion of the tongue depressor are for illustrative purposes only and form no part of the claimed design.
